United States Patent Office.

WINFIELD S. GROVE, OF PHILADELPHIA, PENNSYLVANIA.

Design No. 4,628, dated February 7, 1871.

DESIGN FOR A SHOW-CASE.

The Schedule referred to in these Letters Patent and making part of the same.

I, WINFIELD SCOTT GROVE, of Philadelphia, county of Philadelphia, State of Pennsylvania, have invented or produced a Design for a Show-Case, of which the following is a specification.

In the accompanying drawing—

Figure 1 is a perspective view of a show-case made in accordance with my design, and

Figure 2, an end view of the same.

A represents the top of the show-case;

B, the base of the same;

C, the front;

D, the back; and

E E, the opposite ends.

The top and bottom are flat and parallel to each other. The ends E E may be either vertical or inclined, and the front C and back D of the case are both inclined in the same direction and at the same or different angles.

I prefer, however, that the front C should be inclined at a somewhat greater angle than the back, in order to enable objects within the case to be distinctly seen through the same, and that the back, which may consist of mirrors, should only be inclined at such an angle as will enable objects upon the bottom of the case to be reflected in the same when looking through the inclined front.

I claim—

The design for a show-case, substantially as described and as represented in and by the accompanying drawing.

In testimony whereof I have signed my name to this specification in the presence of two subscribing witnesses.

Witnesses:

W.M. A. STEEL,

F. B. RICHARDS.

W. S. GROVE.
